RADIO RECEPTION

Walter Lyons, Wenonah, N. J., assignor to Radio Corporation of America, a corporation of Delaware

Application February 5, 1944, Serial No. 521,174

3 Claims. (Cl. 250—20)

1

My present invention relates to the amplification and translation or demodulation of high frequency waves. In particular, it relates to circuits for the translation of voice or code modulated high frequency waves.

For communication purposes it is desirable to have a radio receiver which is adapted for the reception of either code or telephonic signals. One object of my present invention is to provide such a receiver which operates for the efficient reception of either type of signal and which may be readily converted from code reception to voice reception or vice versa. Another object is to provide a circuit arrangement which utilizes vacuum tubes in an efficient way whereby a small number are employed with high utility in the reception of code and voice signals.

Other objects, advantages and features will be self-evident from the more detailed description to be given later and also from the following overall brief description of my improved radio receiver.

Received high frequency waves bearing code or voice signals are amplified, heterodyned down to a convenient intermediate frequency and further amplified. For the reception of voice signals, the intermediate frequency waves are fed to the triode section of one tube acting as a detector. The detected waves are fed to a triode section of a second tube which serves as an amplifier. The amplified voice waves are utilized in any desired way. A diode section of the second tube is used, as will be more fully explained hereinafter, for automatic volume controlling purposes in the R. F. and I. F. stages of the receiver. A second diode section of the second tube is used as a "gate" to prevent the application of positive voltages to the grids of earlier stages of the receiver despite the use of such voltages injected into a portion of the volume controlling circuits.

The volume controlling diode circuit heretofore mentioned is also utilized for exciting certain amplifying and limiting tubes employed in the reception of code signals. When receiving code signals a local oscillator is brought into play which feeds beating waves to the detector section of the first tube. The resulting beat, adjusted to an audio frequency, is fed to the amplifying section of the second tube mentioned above for monitoring purposes.

In the more detailed description which follows, reference will be made to the accompanying drawings wherein:

Figure 1 is a block diagram of the radio frequency and intermediate frequency stages of a

2

radio receiver showing part of the automatic volume controlling circuits;

Figure 2, consisting of Figures 2a and 2b taken together, illustrates an arrangement of tubes and circuits for utilizing the intermediate frequency output of the system shown in Figure 1 for reproducing the voice or code signals received on the antenna system of Figure 1; and

Figure 3 is a more detailed illustration of a coupling unit utilized in the apparatus of Figure 1.

In Figure 1, which illustrates diagrammatically the radio frequency and intermediate frequency stages of the receiver, the incoming waves are picked up upon an antenna 60 and fed to a first radio frequency amplifier 62. The output of the various radio frequency stages may be fed, by plug-in coil and condenser circuits 64, 66, to succeeding R. F. amplifier stages such as 68. The output of the radio frequency amplifier stage 68 is fed to a first detector and oscillator stage 70 in which the amplified radio frequency waves are heterodyned down to a suitable intermediate frequency.

For example, the receiver may be designed to receive waves in the band ranging from 1.5 to 18 megacycles and the oscillator of the first detector and oscillator 70 may be adjusted in frequency so that the intermediate frequency produced and amplified in the intermediate frequency amplifying stages 72, 74 and 76 is of the order of 735 kilocycles.

In order to enable the receiver to operate over such a wide range, plug-in coil and condenser apparatus is provided for the coupling between such stages as radio frequency stages 62 and 68.

As shown in Figure 1, typical plug-in apparatus would consist of a primary coil 90 tuned by a fixed condenser 92 and variable iron core 94. The output of circuit 90, 92 would be fed through the link consisting of the small secondary 96 and coupling condenser 98 to the next coupling condenser 100 of the plug-in arrangement 66. The waves fed through coupling condenser 100 are then fed to the small primary 102 which inductively feeds the secondary 104. Secondary 104 is tuned both by means of a condenser 106 and variable iron core 108.

The mechanical arrangement for plug-in coupling apparatus such as 64 or 66 of Figure 1 is illustrated in greater detail in Figure 3. Figure 3 illustrates the apparatus within either rectangle 64 or 66 of Figure 1. Referring to Figure 3, metal can 64 is clinched to the insulating base 200 in any suitable way. Can 64 helps keep the

paper form 202, cemented to the base 200, in place. That is, the under surface of the top of can 64 presses against the top of form 202. The large coil 90 is wound on the upper portion of the form 202 and the smaller secondary 96 is closely wound and arranged about $\frac{1}{8}$ th inch below the coil 90 on form 202. Condensers 92 and 98 correspond to smaller condensers within rectangle 64 of Figure 1. Appropriate connections are brought out from the various elements within the can 64 to the prongs mounted beneath the base 200.

The iron plug 94 is mounted upon a screw-threaded shaft 205 in turn screwed into an internally threaded opening in the key 208 also mounted on the base 200.

Turning now to Figure 2, that is, to both Figures 2a and 2b constituting Figure 2, amplified waves of intermediate frequency are fed from the tuned primary circuit 2 to the transformer secondary in the tuned circuit 4. The energy resonated in circuit 4 is divided into two paths. One path feeds a monitoring arrangement of tubes and circuits and the energy in the other path is rectified for A. V. C. purposes and for operation of recording apparatus when code signals are being received.

For voice reception the output of tuned circuit 4 is fed through condenser 6 on to grid 5 of tube 8. Grid 5, cathode section 1 and plate 9 of tube 8 operate as a detector, as a result of which the audio signal appears in the circuit of plate 9 of tube 8. This audio signal is fed through condenser 10 and potentiometer 12 to the grid 13 of tube 120. The amplified output appearing in the circuit connected with plate 15 of tube 120 is fed through transformer T113 to line terminals L and G of jack J107. If desired, the voice output of transformer T113 may be fed simultaneously to jack 106 and thence to earphones for monitoring purposes.

The bias on grid 5 of tube 8 is produced by cathode current flow through the cathode 3 of tube 8 and biasing circuit BC1 consisting of resistor R135 and condenser C155. Additional bias is provided by grid leak condenser R137 and its condenser C166.

It will be noted that while amplified intermediate frequency energy is fed through condenser 6 to the grid 5 of tube 8 for rectification and reproduction of the transmitted voice signal, another portion of the intermediate frequency waves is fed through lead 14 to the upper diode plate 17 of tube 120. This I. F. voltage operates on the electron stream from the cathode 11 of tube 120 to produce a voltage drop across the resistor R129 (Fig. 2b). As illustrated in Fig. 1 this voltage drop across resistor R129 serves automatically to control the volume or gain in the radio frequency and intermediate frequency amplifiers.

In this regard, point X of Figure 1 is connected to point X of Figure 2b and in this A. V. C. circuit, R130 is an isolating circuit resistor, and C189 is a by-passing condenser. R154 of Figure 1 is a variable bank of resistors for controlling the automatic gain control time constant.

Since the reception of C. W. code signals represents a substantial part of the service to which the present receiving system may be put, these variable A. G. C. time constant circuits have been provided. Three time constants have been provided by virtue of the R154 circuit although two may suffice for most cases. As shown, with one resistor in circuit at 154 the time

constant has a value of approximately one second; in another position of the switch the time constant has a value of one-tenth of a second; and in the third position one one-hundredth of a second. If two time constants are used it is preferable that they be made approximately one second and one-twentieth of a second. A fast time constant is required when recording signals that have a fast fading characteristic causing drop-outs and the A. G. C. is required to follow this. A slower time constant is desirable when noise occurring between code pulses is encountered.

Resistors 20, 22, 24 and 26 of Figure 1 are isolating resistors and may be one megohm each in value. Resistor 28 is another isolation resistor and may be, for example, 100,000 ohms in value. Resistance R124 of Figure 1 is a voltage dropping resistor and operates to apply a small positive voltage through a lead, as shown in Figure 1, to the automatic gain controlling circuit.

It will be noted, referring to Figure 2a, that diode plate 19 of tube 120 is connected through lead 32 to point X on the A. G. C. circuit. The action of this connection to the electrode 19 of tube 120 is to prevent excessive positive voltages from being introduced into the automatic gain controlling circuit. During operation with a workable signal, a negative voltage is, of course, developed across resistor 129 (Fig. 2b) of such value as to impress a resultant negative voltage on the grids of the various gain controlled stages through the resistors 20, 22, 24 and 26 of Figure 1.

One purpose of applying the positive voltage through resistor R124 of Figure 1 is to enable high negative voltages to be developed across resistor R129 of sufficient negative value to operate the keying circuits when code signals are being received. The positive voltage applied or injected through R124 of Figure 1, however, prevents the high negative voltage developed across resistance R129 from being applied through the gain controlling circuits except in such values as to enable desired operation of the system over the automatic gain control range.

Also for diversity reception it is desirable to have as high as possible an E. M. F. on the diode 17. This high voltage will overcome the sum of the contact potential and rectified interference noise potential. Thus, with a relatively small signal on the antenna 60, say, one-half of one microvolt, a voltage of twenty volts may be built up across the diode resistor in circuit with diode plate 17. The positive potential placed upon the A. V. C. string 20, 22, 24 and 26 delays the A. V. C. action and enables this voltage to be built up, as a result of which some twenty-two or twenty-three volts may be secured for cutting off the other receivers of the diversity system. This high voltage also is useful for operation of the keying relay which requires high excitation.

In other words, development of high voltage across resistor R129 enables efficient operation of the keying relay and recorder circuits and yet this high voltage is useful for A. V. C. purposes by virtue of the partial compensating action of the injected B voltage into the A. V. C. network through resistor R124. Injection through R124 does not mean that positive voltage is impressed on the grids, rather it means that the grids are fed with proper negative potentials for good operation. Should, for some reason, positive potential leak through to X (Fig. 1) conductor 32 70 will impress this voltage on 19 (Fig. 2a), thereby

immediately and effectively grounding the grids connected to the A. V. C. string. When the plate 19 is negative, conductor 32 is effectively open-circuited. In this way 19 acts as a "gate," preventing the grids in the A. V. C. string from going positive.

For voice reception, and also, if desired, for monitoring code signals, a bank of tone control condensers S105 (Fig. 2a) may be provided as illustrated. The condensers of the bank S105, as shown, may be selectively connected into circuit.

For monitoring code reception and recording, switch S40 (Fig. 2b) is closed, which applies plate voltage through the isolating resistors R145 and R144 to the plate 29 of vacuum tube 42. It will be noted that plate 29, cathode 21 and grid 25 of tube 42 are connected to the tuned circuit 44 so as to provide a Colpitts type of oscillation generator. The tuning of this beat frequency oscillator may be controlled within limits by variation of condenser C176. Output of the beat frequency oscillator portion of tube 42 is fed through condenser C171 to the grid 7 of the detector section of tube 8 (Fig. 2a). As a consequence, audio frequency beat waves are produced in the plate circuit section, including plate 9, of tube 8 and are fed through condenser 10 to the grid 13 of tube 120 for amplification. The amplified tone so produced may be heard in phones connected with jack J106.

Typical examples of waves to produce a suitable tone in the jacks for monitoring code signals are an intermediate frequency of 735 k. c. and a frequency for the local beat frequency oscillator 736 k. c., as a result of which the tone heard in the phones connected to the jack J106 will be of the order of 1,000 cycles.

For detecting and recording code signals, as before, a part of the intermediate frequency waves are fed through lead 14 to the plate 17 of tube 120. The rectified voltage appearing across resistor R129 (Fig. 2b) for code reception is not only used for automatic volume control, as before explained, but is also fed to the recording apparatus through switch S104 when closed. Closure of switch S104 impresses the voltage developed across resistance R129 upon the grid 23 of tube 42. Resistor R143 is provided to connect the grid 23 to ground when switch S104 is open and is of such value, as for example ten megohms, as not to interfere with operation when switch S104 is closed.

Condenser C158 is provided to by-pass high frequency noise voltages to ground without interfering with the relatively lower frequency code signals and to wipe out undesired modulations which may appear on the code signals. The amplified and limited voltage on plate 21 of tube 42, which amplified voltage is controlled by the input on the grid 23 thereof, is fed through condenser C177 on to the parallel connected grids 31 and 33 of tube 50. It will be noted that the plates and cathodes of tube 50 are also connected in parallel, in this way effectively increasing the power output of the tube 50 which is to be applied to the recorder terminals. The output of tube 50 is fed to the recorder through condenser C178, inductance coil L126 and recorder jack J108. C179 is a shunting radio frequency bypassing condenser.

It will be noted that the signal sections of tube 42 and tube 50 act as limiting amplifiers. This action is secured by virtue of the fact that grid 23 of tube 42 is operated at zero D. C. bias normally in the absence of signal and the grids of

tube 50 are biased to plate current cut-off by virtue of voltage applied to the grids thereof through lead 34.

Because of the biasing circuit chosen for the tube 42, it is essential that the voltage developed across R129 be large so as to quickly bring grid 23 of tube 42 to a value sufficient to produce limiting or plate current cut-off. As before explained, this voltage may be developed across R129 and yet also may be employed for A. V. C. By the action of the circuit including the plate 19 of tube 120 any positive voltage which might be impressed on the grids or otherwise due to tubes going gassy or due to other conditions, is immediately grounded and prevents the application of positive voltages to the grids of the automatically volume controlled stages. The grids may normally be maintained about three-quarters of a volt negative with respect to their cathodes under no signal condition. This follows for if a positive voltage is applied to 19, it effectively is reduced to cathode potential because of electron current flow.

Additional receivers may be provided for diversity reception. In this event, terminals D and A of the jack J109 are connected in parallel. This will automatically connect a series of resistors R129 in parallel. However, if desired only one or more of such resistors may be left in circuit even though two, three or more receivers may be so connected in parallel. A good practical number of receivers for diversity action is three, although as many as six or seven may, if desired, be employed.

Having thus described my invention, what I claim is:

1. In combination, an amplifier amplifying high frequency waves modulated with code signals, a first tube having a detector section, a second tube having a relatively low frequency amplifier section and a diode detector section, a third tube having an amplifying section and an oscillator section, circuits for applying waves from the high frequency amplifier to the detector section of the first tube, circuits for applying waves from the oscillator section of the third tube to the detector section of the first tube, a circuit for applying the resultant relatively low frequency beat to the amplifying section of the second tube, means utilizing the amplified output of the amplifying section of the second tube for monitoring purposes, a circuit for supplying high frequency waves to the diode section of the second tube, a resistor across which voltages are developed by rectifying action of the diode section of the second tube, and circuits for utilizing said voltages to control the amplifying section of the third tube and to automatically volume control said high frequency amplifier, and a utilization circuit coupled to the output terminals of the amplifying section of the third tube.

2. Apparatus as claimed in the preceding claim, and including a voltage dropping resistor in said volume controlling circuit through which a positive voltage is applied in order to partially compensate the voltage developed in said resistor which is included in said diode detector section.

3. Apparatus according to claim 1 and including means for maintaining the grid of the amplifying section of the third tube at substantially zero potential with respect to the cathode, an additional amplifier complemented at least by triode electrodes, means for coupling the plate of said amplifying section in the third tube to said

additional amplifier and means normally effective for applying a plate current cut-off bias to the grid of said additional amplifier.
